UNITED STATES PATENT OFFICE.

HARRY W. HILL, OF SOUTHBRIIDGE, MASSACHUSETTS, ASSIGNOR TO AMERICAN OPTICAL COMPANY, OF SOUTHBRIIDGE, MASSACHUSETTS, A VOLUNTARY ASSOCIATION OF MASSACHUSETTS.

GRINDING MACHINE.

Application filed March 8, 1920. Serial No. 363,930.

To all whom it may concern:

Be it known that I, HARRY W. HILL, a citizen of the United States, residing at Southbridge, in the county of Worcester and 5 State of Massachusetts, have invented certain new and useful Improvements in Grinding Machines, of which the following is a specification.

This invention relates to improvements in 10 grinding machines and has particular reference to an improved form of machine adapted for use in the production of ophthalmic lenses.

The leading object of the present invention 15 is the provision of an improved and simplified construction of machine which shall facilitate the rapid and economical production of ophthalmic lenses.

A further object of the present invention 20 is the provision of a machine which shall possess the advantage over the prior art of requiring a less number of parts, have a simplified construction and which shall be substantially automatic in operation, and shall 25 rapidly and efficiently produce ophthalmic or other similar lenses, and which will enable a single machine to handle a much larger number of lenses in the case of strong curves at one operation than has hitherto 30 been possible.

Other objects and advantages of my improved machine should be readily apparent by reference to the following specification taken in connection with the accompanying 35 drawings, and it will be understood that I may make any modifications in the specific details of construction shown and described within the scope of the appended claims without departing from or exceeding the 40 spirit of my invention.

Figure I represents a vertical sectional view through a machine embodying my improvements.

Figure II represents a similar view showing the parts shifted to a different position as occupied during the grinding operation.

Figure III represents a side elevation of the machine.

Figure IV represents a front view of a 50 slightly modified form.

In the drawings, the numeral 1 designates the main table or base portion of the machine having suitably journaled therein the spindle 2 driven as by the pulley 3 to cause

the spindle to rotate. The upper end of the 55 spindle is preferably provided with a cone or similar point 4 fitting in the socket 5 of the bowl lap 6 which is preferably substantially hemispherical in form, provided at its outer edge with the outwardly and upwardly extending abrasive receiving flange rim 7 having cooperating therewith the scraper 8 for directing the abrasive against the lenses to be ground. These lenses 9 are carried by the block 10 which may be of any ordinary 60 construction, as for instance a semi-spherical cast iron base portion with an outer pitch or adhesive coating 11 which serves to secure the lenses in place. Centrally secured to the block 10 is its spindle or arm 12 having at 65 its outer end the socket 13 to receive the ball 14 on the oscillating pin 15 carried by the transversely shiftable arm 16. This arm 16 slides through the guides 17 actuated as by the cam 18 to transversely move the pin 15. 70 A weight 19 mounted on the upper end of the pin 15 serves to actuate the same in the direction of the lap 6. The cam 18 is preferably carried by the drive shaft 21 which is further connected as by the belt 22 with 75 the pulley 3 on the spindle 2.

The operation of my improved machine will probably be best understood by reference to Figures I and II, from which it will be noted that the lap which is to form 80 the desired curve upon the lenses 9 is rotated with the spindle 2, while the lens block 10 fills up the major portion of the lap leaving the space as at the left which contains a considerable portion of abrasive 85 such as emery or similar substance suspended in water whereby it is carried between the block and lap to suitably abrade the several lenses 9. It will be understood that as the containing lap is rotating at 90 a fairly high rate of speed centrifugal action will tend to throw the abrasive outward toward the side of the bowl and into the space enclosed by the rim 7 where it will be met by the scraper member 8, which 95 will interrupt the swirl of the material and shoot the same forward centrally against the lens block. Inasmuch as the connection between the spindle 12 and lens pin 15 is a ball and socket one, and since the friction 100 is much greater at the upper side of the lens block than at the lower due to the difference in speed of the adjacent portions 105

of the lap, the turning of the bowl will cause the block to rotate or drift around thus continuously changing the position of the lenses being ground and allowing the 5 lap to operate uniformly on the same to produce lenses all having the same spherical curve. To increase the break-up action and prevent any grooving of the lenses due to the block unduly remaining in stationary 10 position a transverse oscillatory motion is applied to the pin 15 as by the cam 18 shifting the pin transversely and thus causing the block to slide around somewhat within the bowl bringing the upper edge higher 15 or lower as the oscillation is in the one direction or the other and supplying extremely satisfactory break-up for the grinding operation.

It is to be understood that while I have 20 particularly described the parts of my invention as disposed with the lap as the outer or concave member and the block as the inner or convex member, if desired the character of the parts may be reversed in that 25 the lenses may be carried on the interior of the bowl and the member inserted within the bowl may be the lens grinding or polishing member in the event that contrageneric curves are to be formed on the 30 lenses and it is to be understood that I consider this adaptation of the parts as equivalent and both as falling within the scope of the appended claims.

I would further call particular attention 35 to the shape of the upper portion of the grinding lap, in that the flange rim 7 is at an angle so that abrasive material crowded up out of the lap during the grinding 40 operation onto the shelf will, if in fluid form, have a tendency to flow back down into the central portion of the bowl, while the upstanding outer rim flange 23 serves to absolutely stop any material crowded up or thrown outward by centrifugal action,

thus affording a space receiving the abrasive 45 material so that it may be satisfactorily engaged by the scraper to throw the same back centrally of the lap.

It will be understood that in the interest of lightness and to make the lens blocks more readily handable, they are preferably hollow, as is indicated in Figure I, while to prevent the abrasive from being wasted, filling up this hollow and making the block unduly heavy as well as unduly slimy and 50 disagreeable to handle, I preferably slip over the spindle 12 the light cap member 21 having the rim 25 adapted to be sprung over the outer edge of the lens block and make a tight joint therewith, thus closing 55 up the hollow central space and keeping out the abrasive material therefrom.

I claim:

1. In a lens grinding machine, the combination with a bowl member having an outwardly deflected angularly disposed flange at the upper edge thereof, and an upstanding rim encircling the flange, of a scraper supported adjacent the bowl and arranged to contact the flange and a portion 60 of the bowl.

2. In a device of the character described, the combination with a hollow or bowl like grinding lap, of means for rotating the lap, an outwardly flaring rim formed continuous with said lap and terminating in an upstanding edge, and a scraper having a portion depending within the bowl of the lap for engaging the operative wall thereof, and a portion in engagement with the 75 flaring rim to remove and inwardly deflect abrasive thrown thereinto.

In testimony whereof I have affixed my signature, in presence of two witnesses.

HARRY W. HILL.

Witnesses:

H. K. PARSONS,
E. M. LAFLER.
